UNITED STATES PATENT OFFICE.

JACQUES PERL, OF BERLIN, GERMANY.

TOBACCO PIPE, CIGAR, CIGARETTE, OR HOLDER THEREFOR.

Application filed December 29, 1921. Serial No. 525,759.

To all whom it may concern:

Be it known that I, JACQUES PERL, a citizen of Germany, and a resident of Berlin, Germany, have invented certain new and 6 useful Improvements Relating to Tobacco Pipes, Cigars, Cigarettes, or Holders Therefor, of which the following is a specification.

This invention relates to tobacco pipes, 10 cigars, cigarettes or holders therefor and has for its object to provide for more efficient cooling of the smoke, the absorption of moisture or aqueous vapour and the retention of any heavier volatile substances entrained thereby, the unpleasantness of 15 which is particularly noticeable when the tobacco is nearing final combustion, especially in the case of short-stem tobacco pipes.

Heretofore attempts have been made to cool the smoke by filtration or in cooling 20 chambers or the deleterious substances in the smoke have been absorbed or neutralized by the chemical action of substances carried by a suitable porous carrier.

According to the present invention, the 25 water vapour or steam generated during the combustion of the tobacco is utilized to cool the smoke by causing the products of combustion of the tobacco to come in contact with salts which combine with water and in so doing absorb a comparatively large amount of heat. Such salts may be those used, for example, in refrigerating mixtures whose action also depends on the absorption of heat when dissolved. The salts should 30 not however be volatile or give off any volatile noxious or unpalatable substances or be of too hygroscopic a nature.

For the purpose of the invention, the salts employed may, for example, be crystallized 40 sodium acetate, sodium sulphate (or Glan- ber's salt), ammonium nitrate or the like.

The salts are preferably interposed in suitable form in the smoke current, such as, for example, in the form of a plug or cartridge inserted in the pipe stem. Preferably the salts are mixed with or incorporated in an excess of highly porous substance, such as granulated carbon, silica (or kiesel- guhr), pumice-stone, blotting paper, or the like, in order to provide a sufficiently large area in contact with the smoke.

Such cartridges may also be employed in cigar or cigarette tips, mouthpieces or holders.

55 Experiments with the artificial production of smoke by means of a jet pump have

shown that by the use of a cartridge containing 3 grams of a mixture of sodium acetate and granulated wood charcoal in the proportion of one to three, the maximum 60 temperature of the smoke from a short-stem tobacco pipe in the first test was reduced by 9 degrees and on a second test using the same substance again, the temperature was reduced by 7 degrees (centigrade). 65

As the temperatures in question vary slightly above blood heat, and the temperature of the smoke may exceed 40° C., the enjoyment and pleasantness of the smoke is considerably enhanced by such reduction of 70 the temperature as that above quoted.

The use of these salts has also the further advantage that the retention and cooling of the greater part of the moisture effects the retention of a greater part of the tarry volatile substances of higher boiling point entrained with the moisture, thus improving the palatability and enjoyment of the tobacco smoke. In addition, the tobacco and particularly the unconsumed residue in the 80 pipe bowl is kept dry by reason of the moisture or condensates being prevented from returning along the stem to the bowl. Consequently more efficient tobacco consumption is attained than heretofore usual, as frequently 15 to 20% of the tobacco was heretofore wasted.

The plugs or cartridges may be of various sizes and shapes to suit different tobacco pipes. The mixture contained in the cartridge may be obtained by simply mingling the porous substance with the salt or the porous substance may be impregnated with a solution of the salt and the latter thereafter crystallized on the porous substance. In 90 the case of cigar and cigarette tips or mouthpieces, the plug or cartridge may be of conical shape. Such paper tips or mouthpieces may also be used as mouthpieces for small 95 pipe bowls.

The plug or cartridge may consist of an outer preferably porous or perforated envelope through which the smoke may percolate with or without perforated or porous ends, the cartridge being filled with the salt or mixture hereinbefore described.

The accompanying drawing illustrates one embodiment of my invention by way of example.

Fig. 1 is a side view of a cartridge made 110 according to this invention. Figs. 2 and 3 are opposite end views thereof. Fig. 4 is a

longitudinal sectional view of the cartridge.

In the construction shown, the salt which effects the cooling of the tobacco smoke is carried by a cartridge made of porous paper 5 rolled to the shape shown and impregnated with a solution of the salt. My invention is not however limited to the use of the cartridge shown.

It is to be understood that the term "refrigerating substance" in the appended 10 claims is to be construed as excluding salts which absorb only a limited amount of heat from the solvent during passage into solution and that the term "refrigerating substance" therefore excludes common salt 15 which absorbs only about 18 calories per gram of solvent and which it has already been suggested to use in the bowl of a to-

bacco pipe for absorbing or neutralizing nicotine, but not for cooling the tobacco 20 smoke.

Claims:

1. As an article of manufacture, an absorption device for cooling tobacco smoke and adapted to be placed in the smoke path 25 of a smoking device, comprising sodium acetate and a porous carrier therefor.

2. As an article of manufacture, a cartridge for cooling tobacco smoke comprising 30 a porous carrier impregnated with a refrigerating substance capable of absorbing heat when dissolved in water.

In testimony whereof I hereunto affix my signature.

JACQUES PERL.
